HIRAM SMITH AND THOMAS J. LUMIS, OF NORWICH, CONNECTICUT.

Letters Patent No. 60,800, dated January 1, 1867.

IMPROVEMENT IN MACHINES FOR TENONING BLIND-SLATS AND BORING THE STILES.

The Schedule referred to in these Letters Patent and making part of the same.

TO ALL WHOM IT MAY CONCERN:

Be it known that we, HIRAM SMITH and THOMAS J. LUMIS, of Norwich, in the county of New London, and State of Connecticut, have invented a new and improved Machine for Tenoning Slats and Boring Stiles; and we do hereby declare that the following is a full, clear, and exact description thereof, reference being had to the accompanying drawings, making a part of this specification, in which—

Figure 1 is a plan view of the machine.

Figure 2 is an elevation of the front of the same.

Figure 3 is a cross-section, taken through the machine in the vertical plane indicated in red lines $x\ x$, fig. 1.

Figure 4 is an elevation of one end of the machine.

Similar letters of reference indicate corresponding parts in the several figures.

This invention relates to certain improvements on machinery for boring blind-stiles, and also for tenoning slats for window blinds. The invention consists in combining with a boring tool a spring gauge, which is so constructed and applied to an adjustable bearing on the arbor support of the boring tool that it will serve as a means for stopping and holding the stiles upon their table at the required points for boring the holes in these stiles, after the required distance apart for the holes has been once determined, as will be hereinafter described. It also consists in sustaining the slats between two turning centres during the operation of forming the shoulders on the ends of these slats; said centres being so constructed and operated as to serve, in conjunction with the shoulder cutters, for producing the tenons on the slats, as will be hereinafter described.

To enable others skilled in the art to understand our invention, we will describe its construction and operation.

In the accompanying drawings, A represents the frame of the machine, and A' a long driving-belt drum, which is supported at its ends in bearings upon the lower cross-beams at the ends of the frame. C' C' are two horizontal shafts which extend longitudinally across the top of the frame A, and have their ends supported in bearings upon the upper cross-beams of this frame. The longitudinal shaft, C, has three forked standards, D D' D'', secured rigidly to it; which standards serve as bearings for three arbors a a a', upon which small belt drums, b b b', are keyed, that receive rotary motion from the drum, A', through the belts, as shown in fig. 1. The two arbors, a a, have circular-saws, c c, suitably secured on their inner ends; which saws are designed for cutting the shoulders at the ends of the slats and leaving the tenons thereon. To one end of the arbor, a', an auger, a'', is applied for boring the stiles which receive the tenons on the slats. This operation of boring will be hereinafter described. In front of the two saw-carrying arbors, a a, two standards, E E, are secured to a rocking-shaft C'', which standards are forked like those which carry the auger and saw arbors above described. These two forked standards, E, serve as bearings for two arbors d d, which receive a rotary motion from the drum, A', by means of belts, e e, and small belt drums, e' e'', between the forked ends of the standards. On the inner or opposite ends of arbors d d, tubular centres, d' d'', are formed or suitably secured, which terminate in sharp cutting edges for cutting in a direction with the length of the slats that are confined and centered between them. The outer ends of the arbors, d d, have annular grooves formed in them, which are for the purpose of receiving the forked ends of arms F F. These arms are secured at their lower ends to reciprocating rods f f, which pass through their respective standards, E E, directly above, and parallel to, the shaft C'', and enter a circular box G which is secured upon this shaft, C'', between said standards E, as shown in figs. 1 and 2. The inner ends of rods f f are curved and secured on opposite sides of the centre of box G to a vibrating lever, G', which is pivoted to the central pin of said box. One end of the lever, G', projects through an oblong slot through the front edge of the box G, so that it can be conveniently taken hold of and vibrated. By means of lever G the attendant causes the two centering cutters, d' d'', and their arbors, to advance toward each other and retreat, at pleasure, while they are rotating. In front of the centering cutters are two standards H H, which are secured to the front rail of frame A, so that they can be adjusted further apart, at pleasure. The upper ends of these standards are curved, so as to be brought near the centering cutters, and are provided with vertically adjustable slat rests g g, for gauging the slats and supporting them in a proper position to be gripped between said centering cutters. The slat rests, g, are vertically adjustable for adapting the machine to tenon slats of different widths, and the standards, H, are laterally adjustable to adapt the machine for slats of

different lengths. The standards, D D, and E E, as well as the box G, are secured to their respective shafts C C', so that they can be loosened and adjusted for slats of different lengths. The machine being adjusted as above set forth for producing a tenon on a slat of a given length, such slat is put upon the rests, g g, and gripped between the centres d' d', after which the shaft, C', is moved about its axis by the operator with his hand on lever G', and the rotating slat brought up to the rotating saws c c, which cut into the slat in a direction at right angles to the axis of the centering portions d'. When the saws complete their work, the operator moves the lever, G', quickly to one side, and thus causes the cutters, d' d', to form the rounded tenons. The lever, G', is then moved in an opposite direction to release the slat, and downward to bring the centering cutters in a position to gripe another slat. In order to have the tenons on the ends of the slats enter the holes in the stiles readily, the inner ends of the holes of the centres, d' d', are contracted, so as to give a slight taper to the extremities of the tenons, as shown in fig. 5. It is obvious that the same result will be produced by having the saws, c c, advance to the slat instead of having the slat moved up to the saws. I have applied stop pins, j, on the oscillating shaft, C', and frame A, for determining the length of vibration of this shaft, and preventing the centering cutters from moving too far forward or backward. As the axes of the arbors, d d, do not move concentric with the axis of the main driving drum A', we employ two belt-tighteners k k, which are secured to the lower ends of the standards E, so as to keep the two belts, e e, always under proper tension when the slat is being tenoned. These arms, k k, are shown clearly in figs. 2 and 4. The outer end of the arbor, a¹, is adapted for receiving auger bits, a², for boring the mortises in the stiles, J, for receiving the tenons on the slats. The stile to be bored is supported upon a transverse beam, K, which is sustained in a horizontal position at one end of the frame, A, by means of jointed arms l l, which admit of said beam being raised or lowered without moving it out of a horizontal position. An arm, m, is secured by means of a set-screw to the shaft C, near the standard D'; and to the outer end of this arm another arm, m', is secured, which projects upward, and carries a spring pin n, the axis of which is parallel to the axis of the arbor a¹, as shown in fig. 1. This spring pin, n, has a head formed on one end, and its opposite end is slightly tapered, so as to enter the holes made in the stile by the auger bit a², and not only hold the stile down upon the table or beam K, but press the stile up firmly against a ledge which is formed on this beam. The arm m' is connected to arm m by means of a set-screw, so that the axis of pin n can be adjusted up or down, or at any required distance from the axis of the auger a², for boring stiles of different thickness, and for boring holes at different distances apart, as may be required. The pin, n, serves as a gauge for adjusting the stiles up to the auger after one hole has been bored in a stile. This spring pin will render unnecessary the marking off of each stile to find the position or distance for boring the holes. A vibrating arm, L, which is pivoted to the shaft C, is connected at its upper end to the arbor, a¹, of the auger, so as to allow this arbor to rotate freely, and at the other end to a treadle, N, by means of which the attendant can move the arbor and auger toward the stile, J, for boring the holes. The spring s, shown in dotted lines, fig. 2, moves the auger and its arbor back when the operator releases the treadle.

Having thus described our invention, what we claim as new, and desire to secure by Letters Patent, is—

1. The use of vibrating centering cutters d' d', in combination with circular saws c c, the said cutters and saws being brought into action by means such as described, or the equivalent thereof, and operating substantially as described, for the purpose of forming tenons on slats.
2. Constructing the tenon cutters, d' d', in such manner as to compress and taper the extreme outer ends of the tenons on the slats, substantially as described.
3. The combination of tubular longitudinal cutting and centering tenon cutters d' d', with slat rests g g, which are constructed and arranged substantially as described.
4. The combination of the shafts C C', adjustable standards D D and E E, with the slat supports H H, which are also adjustable, the said parts being brought into action by means such as described, or the equivalent thereof, substantially as described for the purpose set forth.
5. The spring pin, n, applied to adjustable arms m m', in combination with the stile support K, and boring tool a², substantially as described.
6. Holding the slats by means of the tubular cutters, cutting the shoulders of the tenons with the saws, and then finishing the tenons by means of the same tubular cutters which hold the slats while the saws are operating, all substantially in the manner herein described.
